UNITED STATES PATENT OFFICE.

EDWARD DITHRIDGE, OF ELLWOOD CITY, PENNSYLVANIA.

ENAMELING-FORK FOR BATH-TUBS.

SPECIFICATION forming part of Letters Patent No. 700,021, dated May 13, 1902.

Application filed January 31, 1901. Serial No. 45,473. (No model.)

To all whom it may concern:

Be it known that I, EDWARD DITHRIDGE, of Ellwood City, in the county of Lawrence and State of Pennsylvania, have invented a new and useful Enameling-Fork for Bath-Tubs, of which the following is a full, clear, and exact description, reference being had to the accompanying drawings, forming part of this specification, in which—

10 Figure 1 is a side elevation, partly in section, of my improved apparatus. Fig. 2 is a top plan view of the same. Fig. 3 is a partial side elevation showing the parts in a different position. Fig. 4 is a partial plan view, on 15 a larger scale, of the clamping mechanism for the tub; and Fig. 5 is an end view of the gearing for rotating the fork.

My invention relates to the handling of bath-tubs in the enameling operation and is 20 designed to provide an improved apparatus by which the tub may be tilted into any desired position under the control of the operator and by which the tub may also be inserted in the enameling-muffle.

25 In the drawings, 2 represents the vertical post of a crane having a lower rigid arm 3, which swings in a horizontal plane and from which hangs a swiveled yoke 4, through which extends the shaft 5, having the end handle 6. The arm 3 is preferably provided with tension-brace 7, and above it is a second arm 8, which is pivoted at 9 to a loose collar 10, surrounding the post 2. The arm 8 may therefore be swung both in a horizontal and a vertical plane, and its vertical movement may 35 be secured through the wire rope 11, extending over the pulley 12 in the arm, or by any other suitable connections. A link 13 depends from the outer end of the arm 8 and

40 has a swivel connection 14 with a collar 15, which surrounds and supports the bearing 16. The shaft 5 is rigidly secured within the rear end of the two-part bearing 16, within which extends the rear portion of a rotary shaft 17,

45 which carries the fork proper, 18. Ball-bearings are preferably provided within the bearing-sleeve for the shaft 17, as indicated at 19, and the shaft is turned by worm-wheel 20, meshing with worm 21 on the short counter-shaft 22, having bevel-gear connection 23 with a shaft 24, actuated by a small rotary motor 25. Compressed air or other actuating

fluid may be led to the motor by a flexible connection, and the shaft 17, with its fork, may thus be rotated and locked in any adjusted position by the screw-gearing.

55 The fork 18 is provided with trunnions 26, to the inner ends of which are secured longitudinal plates 27, which fit against the side portions of the tub and are provided at their front and rear ends with loops or eyes 28, which are engaged by spring-catches 29, whose shanks are secured to end shields 30. These end shields are formed to fit the end of the tub and are provided with pulleys 31, 60 over which wind the cords or chains 32, which pass through guiding-eyes 33 to the catches. By turning the hand-wheel 34 the cords may be tightened to disengage the catches 29 from the loops and allow the end shields to be removed after the dredging operation is performed.

70 To turn the tub in the fork to bring it to the different positions desired, I provide one of the trunnions with a worm-wheel 35, engaging a worm on shaft 37, carried in bearings at one side of the fork and having an actuating-handle 38.

75 In the operation of the apparatus the tub is inserted in the forks and the end shields are 80 secured in place, thus fastening the tub to the forks, so that it will not slide out when tilted, as shown in Fig. 3. The operator then turns the tub to its different positions by turning the handle 38 and by actuating the 85 motor to rotate the fork. The enamel is dredged in the tub in these different positions. The tub and fork being raised or lowered by means of the upper pivoted arm 8, the end shields 8 are removed, and the tub being 90 brought to the normal horizontal position is shoved into the enameling-muffle 39 by the operator using the handle 6. When the enamel has been sufficiently heated to glaze the tub, it is drawn out of the muffle and removed from the fork. Another tub is then 95 inserted and the operation is repeated.

The advantages of my invention will be apparent to those skilled in the art, since a simple and effective apparatus is provided 100 by which the tub may be tilted to its various positions with ease and rapidity. The fork itself, by which the tub is introduced to the muffle, is utilized for the dredging of the

enamel instead of using a separate machine, as heretofore.

The mechanism and connections for tilting the tub upon the fork, for fastening it to the fork, as well as the other parts of the apparatus, may be modified without departing from my invention.

I claim—

1. In bath-tub-handling apparatus, a movable support carrying a tub-fork, mechanism for rotating the fork on its axis, and mechanism for tilting the tub to different angles relatively to the fork-axis; substantially as described.
- 15 2. In enameling apparatus, an overhead support, an enameling-fork carried thereby, mechanism for raising and lowering the fork, mechanism for rotating the fork, and mechanism for tilting the tub to an angle with the 20 axis of the fork; substantially as described.

3. An enameling-fork having pivoted side supports for the tub mounted thereon, and end clamping devices for the tub arranged to engage said side supports; substantially as described.

4. In enameling apparatus, a crane-post mounted in stationary bearings and having a horizontally - swinging arm, an enameling-fork supported from said arm, mechanism for rotating the fork around its axis, and mechanism for tilting the tub into an angular position with respect to said axis; substantially as described.

In testimony whereof I have hereunto set my hand.

EDWARD DITHRIDGE.
